DEHUMIDIFIER

Joseph A. Galazzi, Evansville, Ind., assignor to
 International Harvester Company, a corpora-
 tion of New Jersey

Application May 13, 1952, Serial No. 287,565

4 Claims. (Cl. 62—2)

1

This invention relates generally to a dehumidifier and more specifically to a refrigeration system having the evaporator and condenser arranged in series with means for circulating air to be dehumidified into contact with said evaporator whereby the air is cooled to its dew point and water is condensed therefrom onto the surfaces of said evaporator, then into contact with said condenser where the heat removed by the evaporator is returned to the air.

This type of dehumidifier is common in the art and is becoming increasingly popular for the dehumidification of basements, closets and other enclosures where cooling of the air is not required. The major portion of the units being manufactured today are designed with the evaporator and fan of such size that the maximum volume of water will be removed from warm and humid air having a dry bulb temperature of approximately 75° F. and a relative humidity of approximately 80%. However, such a unit is not satisfactory for dehumidification of air having a lower dry bulb temperature and a lower relative humidity, for example 65° F. and 55%, since the dew point of this air approaches the surface temperature of the evaporator. The rate of dehumidification is a function of the difference between the dew point and the evaporator surface temperature so that there will be only a small volume of water condensed from the 65° F. air. The present invention provides a dehumidifier which overcomes this problem.

One object of the present invention is to provide a dehumidifier having a condenser and evaporator arranged in series with fan means for circulating air to be dehumidified first into contact with said evaporator and then into contact with said condenser.

Another object of the invention is to provide means for reducing the volume of air passing into contact with said evaporator when the ambient temperature is low so that the evaporator surfaces will be maintained at a lower temperature.

Another object of the invention is to provide a by-pass opening through which air may be passed into direct contact with the condenser without contacting the evaporator.

Another object of the invention is to provide a damper for regulating the amount of air flowing through the by-pass opening.

Another object of the invention is to provide a receptacle for collecting the water which condenses on the surfaces of the evaporator.

Another object of the invention is to provide a

2

portable dehumidifier which is light in weight and compactly arranged.

Other objects, purposes and characteristic features of the present invention will be in part obvious from the accompanying drawings and in part pointed out as the description of the invention progresses. In describing the invention in detail, reference will be made to the accompanying drawings in which like reference-characters

10 designate corresponding parts throughout the several views, and in which:

Fig. 1 is a perspective view of a dehumidifier unit embodying the present invention.

Fig. 2 is a vertical sectional view of the unit 15 shown in Fig. 1.

Fig. 3 is a cross-sectional view of the unit taken along line 3—3 of Fig. 2.

Fig. 4 is a cross-sectional view of the unit taken along line 4—4 of Fig. 2.

20 Referring to the drawings, a dehumidifier 10 is illustrated which comprises an outer casing 11 having a top wall 12, back wall 13, bottom wall 14, front wall 15 and side walls 16 and 17. Top wall 12 is provided with an inlet opening 18 with 25 vanes 19 secured therein for the purpose of directing air into the opening and protecting the interior of the casing 11 from foreign objects. Front wall 15 is provided with an outlet opening 20 and a door opening 21 spaced thereabove. A 30 screen 22 is secured in outlet opening 20 so that foreign objects will be prevented from entering the opening. Pivotally secured to front wall 15 by hinges 23 is a door 24 which is adapted to close and seal door opening 21 when moved to 35 closed position.

The dehumidifier 10 is provided with a conventional refrigeration system comprising a motor-compressor unit 25, condenser 26 and evaporator 27. The motor-compressor unit 25 is 40 located in the lower portion of the casing 11 and is mounted upon a base 28 which is secured to bottom wall 14 by bolts 29. Condenser 26 is secured to bottom wall 14 by bolts 30 adjacent to outlet opening 20. Evaporator 27 is horizontally 45 disposed adjacent to inlet opening 18 and is secured to back wall 13 and front wall 15 by brackets 31. The refrigeration system is charged with a suitable refrigerant, and during operation, this refrigerant is compressed by motor-com- 50 pressor unit 25 and forwarded through conduit 32 to condenser 26. After being cooled and condensed by condenser 26, the refrigerant is conveyed by conduit 33 to restrictor capillary tube 34 through which it is metered into evaporator 27. As the refrigerant passes through the

evaporator 27, it is heated and vaporized, after which it is returned through conduit 35 to the motor-compressor unit 25 to complete the cycle.

A grille 36 is positioned below door opening 21 and comprises two spaced-apart bar members 37 and 38 which have their ends secured to back wall 13 and front wall 15 by brackets 39, and two spaced-apart bar members 40 and 41 which extend transversely to said bar members 37 and 38 with the ends thereof secured to side walls 16 and 17 by brackets 39. Resting upon grille 36 is a receptacle 42 which is of such size that it may be moved through door opening 21. Positioned above receptacle 42 is a funnel-shaped baffle 43 having downturned edge portions 44 which are secured to the vertical walls of the casing 11. An electric motor 45 is positioned between motor-compressor unit 25 and condenser 26 and is secured to bottom wall 14 by a bracket 46 and bolt 47. The armature shaft 48 of the motor 45 extends toward the condenser 26 upon which is mounted a propeller type fan 49 having the blades thereof pitched to throw air into contact with the condenser 26.

Door 24 is provided with a by-pass opening 50 therethrough with upright channels 51 secured to the inner side thereof adjacent to the edges of the opening. A rectangular shaped damper 52 is slidably secured over the opening 50 with the edges thereof being slidably received by the channels 51. The upper edge of the damper 52 is provided with an outturned flange 53 which may be grasped by an operator when the damper is to be moved. Secured to the outer surface of the door by bracket 54 is a thermostat 55 which is connected to a motor device 56 by conduit 57. The motor device 56 is positioned inside casing 11 and is secured to door 24 by bracket 58. Damper 52 is provided with a projection 59 which is connected to the motor device 56 by a link 60. An increase in ambient temperature would be reflected in the thermostat 55 which causes the motor 56 to close the damper 52. With a decrease in ambient temperature the reverse of this operation will occur and the damper 52 will be moved downwardly to open position by the motor 56.

The dehumidifier is small in size and light in weight so that it can be easily carried by one person. When a room is to be dehumidified the motor-compressor unit 25 and fan motor 45 are energized by a suitable power source until the room air has been conditioned to the relative humidity desired. Either manual controls or automatic controls may be provided for controlling the operation of the unit. With motor-compressor unit 25 energized, the refrigeration system will be cycling as explained heretofore, and the surface of the evaporator 27 will be maintained at a low temperature whereas the temperature of the condenser 26 will be maintained at a high temperature. Assuming that the room air is warm and moist, thermostat 55 and motor device 56 will operate to hold damper 52 in closed position. Fan 49 will draw room air through inlet opening 48 and pass it into contact with the cold surfaces of the evaporator 27, whereby the air will be cooled to its dew point and moisture will condense therefrom onto the evaporator 27. The cooled air will then be pulled downwardly through baffle 43, around receptacle 42, through grille 36 and then forced through condenser 26 by fan 49. As the air flows over the hot surface of the condenser, the heat removed from the air by the evaporator 27 will be

returned, and the air will be reheated to substantially the same temperature as the air flowing through inlet opening 48. The water which condenses on the evaporator 27 will drip onto baffle 43 and be directed thereby into receptacle 42. When the receptacle needs to be emptied, door 24 is opened and the receptacle is removed through door opening 21.

As is well known in the art, air having a low dry bulb temperature and a low relative humidity has a lower dew point temperature than air having a higher dry bulb temperature and a high relative humidity. If the illustrated dehumidifier 10 were operated to dehumidify room air having a low dry bulb temperature and a low relative humidity with damper 52 retained in closed position, there would be only a small amount of water condensed from the air since the temperature of the evaporator 27 would not be much lower than the dew point temperature of the air. To correct this, by-pass opening 50 is provided in door 24. By opening damper 52, a portion of the air being circulated by fan 49 will be drawn through opening 50 and passed into direct contact with the condenser 26. Less air will be circulated over the evaporator 27 so that the temperature of the evaporator will be lowered. There will be a greater difference between the evaporator temperature and the dew point temperature of the air, whereby a larger percentage of the water vapor in the air will be condensed onto the evaporator 27.

The damper 52 may be manually set or automatic means may be supplied for moving the damper as the temperature or relative humidity of the room air changes. In the illustration a thermostat 55 is shown which controls the operation of the motor device 56 in response to temperature changes of the room air. Other means for controlling the motor device 56 could be employed, such as a humidistat or dew point indicator. By proper calibration, the motor device 56 will operate to move damper 52 so that the volume of air flowing through by-pass opening 50 will be regulated in response to the condition of room air whereby the dehumidifier 10 will be operating efficiently at all times.

From the foregoing description, it can be readily seen that a dehumidifier is provided which will operate to remove a maximum quantity of water from room air regardless of the temperature or relative humidity of the air. The unit is compactly arranged and is economical to operate. An ordinary household bucket or pail may be inserted through the door opening for collecting the water which drips from the evaporator. The dehumidifier requires only a small amount of floor space and the outer casing may be designed to blend in attractively with the living quarters of a building.

It will, of course, be understood by those skilled in the art that various changes may be made in the details of construction and arrangement of parts without departing from the spirit of the invention as set forth in the appended claims.

What is claimed is:

1. In a dehumidifier; an outer casing having an air inlet adjacent the top thereof and an air outlet adjacent the bottom thereof; a refrigerant evaporator located adjacent said inlet; a refrigerant condenser located adjacent said outlet; air-propelling means for circulating room air through said inlet into contact with said evaporator, then into contact with said condenser and out said outlet; a receptacle supported under

said evaporator into which the water that condenses from the room air will drain; and a door provided in said casing through which said receptacle is adapted to be moved; said door being provided with a by-pass opening through which room air is drawn by said air-propelling means and passed directly into contact with said condenser and then forced out said air outlet, said by-pass opening being positioned below the top of said receptacle so that any room air drawn into said by-pass opening is prevented from passing over the surface of any condensate collected into said receptacle.

2. In a dehumidifier; an outer casing having an air inlet adjacent the top thereof and an air outlet adjacent the bottom thereof; a refrigerant evaporator located adjacent said inlet substantially at the top of said casing; a refrigerant condenser located adjacent said outlet substantially at the bottom of said casing; air-propelling means mounted substantially at the bottom of said casing for circulating room air through said inlet into contact with said evaporator, then into contact with said condenser and out said air outlet; a receptacle supported immediately under said evaporator into which the water that condenses from the room air will drain directly from the surfaces of said evaporator; a door provided in said casing through which said receptacle is adapted to be moved; said door being provided with a by-pass opening through which room air is drawn by said air-propelling means and passed directly into contact with said condenser and then forced out said air outlet; and a damper slidably secured to said door which is adapted to open and close said by-pass opening.

3. In a dehumidifier; an outer casing having an air inlet adjacent the top thereof and an air outlet adjacent the bottom thereof; a refrigerant evaporator located adjacent said inlet; a refrigerant condenser located adjacent said outlet; air-propelling means mounted substantially at the bottom of said casing for circulating room air through said inlet into contact with said evaporator, then into contact with said condenser and out said air outlet; a receptacle supported under said evaporator between said evaporator and said condenser into which the water that condenses from the room air will directly drain; a door pro-

vided in said casing through which said receptacle is adapted to be moved; said door being provided with a by-pass opening through which room air is drawn by said air-propelling means and passed directly into contact with said condenser and then forced out said air outlet; a damper slidably secured to said door which is adapted to open and close said by-pass opening; and means for regulating the position of said damper in response to the temperature of said room air.

4. In a dehumidifier, a longitudinally upright casing having an air inlet substantially at the top thereof and an air outlet substantially at the bottom thereof, a refrigerant evaporator mounted within said casing substantially at the top thereof immediately below said air inlet, a refrigerant condenser mounted within said casing substantially at the bottom thereof adjacent to said air outlet, fan means mounted within said casing substantially at the bottom thereof adjacent to said refrigerant condenser, said fan operating to draw air through said air inlet into contact with said evaporator, into contact with said condenser and out of said air outlet, a condensate receptacle removably mounted within said casing directly below said refrigerant evaporator and above said fan and said condenser, said condensate receptacle adapted to collect any condensate directly flowing from the surfaces of said evaporator, a door pivotally mounted over an opening provided in one vertical wall of said casing between said refrigerant evaporator and said refrigerant condenser and in alignment with said condensate receptacle, whereby said condensate receptacle may be removed and replaced through said door, an adjustable air vent mounted through the surface of said door operable to allow varying quantities of air to be drawn into said casing below the top of said condensate receptacle and into direct contact with said refrigerant condenser, and out of said air outlet.
